Primary Examiner — Michael A Maharajh

(57) **CLAIM**

The ornamental design for a fascia gun as shown and described.

DESCRIPTION

1. Fascia gun
2. Fascia gun
- 1.1 : Perspective
- 1.2 : Front
- 1.3 : Back
- 1.4 : Left
- 1.5 : Right
- 1.6 : Top
- 1.7 : Bottom
- 2.1 : Perspective
- 2.2 : Front
- 2.3 : Back
- 2.4 : Left
- 2.5 : Right
- 2.6 : Top
- 2.7 : Bottom

FIG. 1.1 to FIG. 1.7 show a fascia gun according to a first embodiment of the present design. FIG. 2.1 to FIG. 2.7 show a fascia gun according to a second embodiment of the present design. The fascia gun is used to massage and relax muscles. The broken lines shown in the drawings illustrate parts of the fascia gun form no part of the claimed design.

1 Claim, 14 Drawing Sheets
